UNITED STATES PATENT OFFICE.

HENRY REICHERT, OF SHIPPENSBURG, PENNSYLVANIA.

IMPROVEMENT IN FLOUR-BOLTS.

Specification forming part of Letters Patent No. 35,953, dated July 22, 1862.

To all whom it may concern:

Be it known that I, HENRY REICHERT, of Shippensburg, in the county of Cumberland and State of Pennsylvania, have invented a certain new and useful Improvement in Flour-Bolts for Separating Flour from Bran; and I do hereby declare that the following is a full, clear, and exact description of the same, reference being had to the accompanying drawings, forming a part of this specification, and in which—

Figure 1 represents a plan or top view of the bolt with the top of the box or cover removed or turned back. Fig. 2 represents a longitudinal section, and Fig. 3 represents a cross-section.

It will not be necessary to describe in detail the construction and operation of flour-bolts in general, since those skilled in the art understand fully the construction and operation thereof. The description will therefore be confined more particularly to the improvement which forms the subject of this patent.

In the drawings, A represents the shaft of the bolt, from which project or extend the arms B B, to which are fastened the bars C C, which support the bolting-cloth D. To the inside of the arms C C are fastened metal spring-bars E. These metal spring-bars are caused to suddenly vibrate at each revolution of the bolt by means of the metal sliding hammers F, which pass loosely through the shaft A, whereby as the bolt revolves the sliding hammers are constantly falling down upon the spring-bars while the latter are passing their lowest point, thus causing the bars C C to have a constant and quick vibration, which is imparted by said bars to the bolting-cloth.

In order that the upper arms and the bolting-cloth which covers them may be vibrated at the same time the lower ones are, the spring-arms E on one side of the shaft A are connected to those on the opposite side by metal rods or straps G G, whereby the vibration caused by the fall of the sliding hammers is imparted to the bolting-cloth both above and below the shaft. The number of spring-arms and ham-

mers will depend upon the size of the bolt employed. By this arrangement the meshes of the bolting-cloth are kept clear, especially of the conical-shaped particles, which often fasten in the meshes of the bolting-cloth and occasion much difficulty. By my improvement they are thrown out of the meshes and pass off with the bran.

The sliding hammers F are regulated by adjusting-plates H, through which they pass.

The plates H are to be confined to shaft A by means of screws a a, or some other proper fastenings which will permit the plates to slide in a horizontal position. In this instance the plates are slotted out, as seen at b b, Figs. 1 and 2.

One end of each plate H is connected to a rod, I, which passes through a hole in an ear-piece, J, fastened to shaft A, after which a spiral spring, c, is passed upon its end, and then an adjusting-nut, e, screwed thereon. (See Figs. 1 and 2.) By screwing up the nuts the plates H can be drawn so close and tight against the hammers F that they will remain stationary, or can be adjusted to fall with any degree of force less than a full blow. The arrangement is such, too, that the adjustment can be made at one end of the bolt, and even when the bolt is in operation, by simply having a door or slide at the end of the box in which the reel or bolt revolves.

My improvement is simple in construction, but very effective in operation.

Having described my improved flour-bolt, what I claim, and desire to secure by Letters Patent, is—

1. The combination of the bars C C, and sliding hammers F, and adjusting-plates H, substantially as set forth.
2. The combination of the rods or straps G G with spring-arms E, hammers F, and arms C C, as and for the purposes set forth.

HENRY REICHERT.
